UNITED STATES PATENT OFFICE.

JOHN GRIESINGER, OF LOS ANGELES, CALIFORNIA.

IDENTIFICATION DEVICE.

Application filed November 27, 1925. Serial No. 71,695.

My invention relates to a means for identifying objects whereby, from a mass or quantity of objects thrown together, a ready and quick assortment may be made, and it has especial reference to a means of and method for applying marks of identification to articles of any description, but chiefly to fabrics, articles of dress and wearing apparel.

10 The invention is designed to eliminate the undesirable, objectionable, and ineradicable inscriptions upon articles, of indicia or other distinguishing characteristics at present generally resorted to by laundries and allied establishments, and the object of the invention is chiefly to provide a simple device by which each piece or article to be laundered may be quickly furnished with a convenient mark of identification, which mark may be quickly 15 dissociated from the articles, without in any wise injuring, marring or otherwise damaging the objects to which applied.

Another object of the invention is to provide a marking device for application to 20 articles, which is provided with indicia of identification and which indicia are always legible and insured against erasure or other obliteration.

These and other objects will appear more 25 fully from the subjoined specification in connection with the accompanying drawing, which is illustrative of a form in which my invention may be embodied, and in which—

Fig. 1 is a perspective view showing my 30 invention as applied to an article of wear.

Fig. 2 is a side elevation of my device.

Fig. 3 is a perspective view showing the 35 device provided with identifying means.

Fig. 4 is a plan view showing a blank 40 prior to bending of same, and

Fig. 5 is a perspective view showing the 45 device prior to application to an article.

My invention broadly considered comprises a means adapted to be attached to the 50 edge of garments, articles, fabrics or other objects, by flexible means which effects a strong bond, and may be readily severed when removal of the identifying mark is desired. The device may be of no greater 55 thickness than the goods or articles to which applied and lying wholly outside the area of the material, it produces no impression or other effect upon the material or object to which attached when the objects are subjected to the pressure of the ironing operation.

In the more specific sense, the invention is shown as comprising a thin piece 1 of metal or any other bendable or flexible material, as 60 linen, or fabric, adapted to be attached to the edge of articles or garments by flexible means, as for instance, by threads 2. For this purpose, the strip 1 of thin material is provided with openings 3 through which the threads 2 may be extended after having first 65 passed preferably between the fold of the hem 4. These openings 3 are arranged preferably in a line and near the center of the strip 1, and penetrate the saddle 5 formed by bending the strip 1. When the strip 1 is 70 bent, as shown in Figs. 1, 2 and 4, one of the branches of the bend is longer than the other, and the portion 6 of the longer branch, which extends beyond the shorter branch is bent over and upon the shorter branch as shown in Figs. 1, 2 and 3, whereby the threads 2 extended through the openings 3 in the saddle 5 and between the branches of the strip 1 are locked and thus prevent the device 75 from dissociation. As shown in Fig. 3, the strip 1 is provided with any desired designation 7, by which identification of the particular article to which the device is applied may be made. In applying the device to an article, the blank or strip 1 is 80 first bent to the form illustrated in Fig. 5, that is, with the respective branches separated and the row of openings 3 forming the line of bend or saddle. In this form, the attachment of the device is made by sewing a 85 thread or threads 2 through the edge of and into the fabric in the plane thereof and through the various openings 3 in the strip 1 to preferably such an extent that the ends thereof project beyond the longer branch of 90 the bended strip 1 as shown in Fig. 5. Thereupon the branches of the bended strip 1 with the threads 3 interposed between them are pressed firmly toward each other, and the extended portion of the longer branch of the strip 1 folded over and upon the shorter branch, whereby the threads 3 are 95 locked and held against dislocation by the bended lip or extension 8. In this manner the device is firmly, but flexibly or hingedly 100 secured to the edge of an article and lies in substantially the same parallel plane. Being wholly outside the area of the object, no indentation, impression or other mark will 105 be made upon the goods when passing same through laundering machinery.

Obviously any kind or form of stitch may

be used for applying the device. A chain stitch may be desirable because the severance of but one thread is necessary to effect ready removal of the device, but any stitch 5 obviously may be employed.

It will be understood that while reference to threads has been made herein as a means for attaching the device to objects, no limitation is thereby contemplated, since

10 any means for attachment of the device to the edge of an object, so that the device lies substantially in the same parallel plane is included hereunder and within the spirit of my invention. It will also be understood 15 that this invention is not limited to applying identification marks to articles of wear but includes the application of distinguishing indicia to any object, where such application is practicable.

20 What I claim, is:

1. An identifying device for articles of fabric, comprising in combination with such fabric, a strip of suitable material having identifying marks thereon and perforations 25 intermediate the ends thereof, and means for attaching said strip to such fabric including threads passing through the edge of and into said fabric in the plane thereof,

said threads being interlocked with said fabric and extending through the perforations in said strip, and said strip being bent upon itself to form contacting parallel plane surfaces with the threads interposed and extended beyond said contacting surfaces, the contacting surfaces of said strip 35 with the interposed threads being interlocked.

2. An identifying device for articles of fabric comprising a strip of suitable material containing identifying marks and perforations intermediate the ends thereof, and means for attaching said strip to the fabric comprising flexible means passing through the edge of and into said fabric in the plane thereof and interlocked with said material, 40 said flexible means extending through the perforations in said strip, the strip being bent upon itself at the line of perforations 45 to form contacting parallel plane surfaces with the flexible attaching means interposed between and extended beyond said contacting surfaces, the contacting surfaces with the interposed flexible means being interlocked.

In testimony whereof I have set my hand.
JOHN GRIESINGER.
